JEWELRY ORNAMENT

Carl Schraysshuen, Providence, R. I., assignor to
Carl-Art, Inc., a corporation of Rhode Island

Application December 23, 1939, Serial No. 310,767

1 Claim. (CL 63—14)

My present invention relates to the jewelry art, and has particular reference to a novel article of jewelry designed to ornament the ear.

It is the principal object of my invention to provide a jewelry ornament for decorating a portion of the ear, and particularly the ear lobe.

Another object of my invention is to provide an ornamentation for the edge of an ear.

With the above and other objects and advantageous features in view, the invention consists of a novel arrangement of parts more fully described in the detailed description following, in conjunction with the accompanying drawing, and more specifically defined in the claim appended thereto.

In the drawing:

Fig. 1 is a diagrammatic section of an ear, to which is attached my novel ornament;

Fig. 2 is a perspective view of the ornament;

Fig. 3 is a bottom view thereof;

Fig. 4 is a side elevation of a modified construction; and

Fig. 5 is a rear elevation thereof.

It has been found desirable to provide a jewelry ornament which decorates the edge of an ear, and which is particularly suitable for ornamenting the ear lobe. I have devised a jewelry ornament having a recess for receiving part of the edge of an ear, and having suitable clamp or other retaining means for locking the ornament to the ear itself. With this construction, an ear decoration is obtained which may be suitably ornamented by using different designs, by utilizing gems and other precious and semi-precious stones, by engraving, or by plating in different colors.

Referring to the drawing, the novel ear ornament 10 is preferably made in the form of a metal stamping or the like having an ornamental front wall 11 and a rear retainer wall 12, the ornament being generally U-shaped in cross section to provide a trough or pocket 13 within which the edge of the ear may be received. The rear retainer wall is provided with a portion 14, preferably in the form of a tab or the like, which receives a lock arrangement such as for example a clamp screw 15 having a central threaded shaft 16 which is threadedly received in a correspondingly threaded opening in the tab 14, the clamp screw having a finger-engageable enlarged end 17 and an ear-engageable enlarged end 18, whereby the arrangement forms an adjustable clamp for

lockingly pressing against the rear side of the ear to lock the ornament on the edge thereof.

The ornamental wall 11, which is exposed to view, may be of any suitable form and may for example have an upstanding ornament portion such as illustrated in Figs. 4 and 5, wherein the ornament 10a has an ornamental wall 11a and a retainer wall 12a, the ornamental wall having an upstanding ornamental portion 19 designed to fit against and to cover the lobe of the ear. The 10 upstanding portion 19 may be of any shape, the illustrated embodiment showing a spiral form, and may be ornamented in any manner desired.

The illustrated ornament is shaped to fit the edge of the ear lobe, as shown in Fig. 1, but may be shaped to fit any edge portion of the ear, to carry out a desired decorative effect, and although primarily designed for an ear ornament, may be modified to ornament the side of a nostril by suitably shaping the parts.

Although a specific clamp screw locking arrangement is illustrated, any other suitable form of lock for maintaining the novel ornament in place may be substituted therefor, such as for example a resilient ear-engaging portion which may be formed by striking up a spring tab from the material of the back wall, or by securing a spring blade thereto in any desired manner.

While I have described a specific constructional embodiment of my invention, it is obvious that changes in the size and shape of the parts, in the length of the edge extension, in the material and the ornamentation used, and in the type of securing arrangement, may be made to suit the requirements for different designs, without departing from the spirit and the scope of the invention as defined in the appended claim.

I claim:

An ear ornament, comprising a sheet metal body portion of arcuate form shaped to provide 40 an elongated curved bottom wall and two side walls extending upwardly therefrom in parallel relation whereby a U-shaped trough having open ends is formed to receive an ear lobe, one of said walls being ornamental, and the other wall having 45 an integral tab extending upwardly therefrom, said tab having a threaded opening, and a manually engageable clamp member having a threaded stem engaging the threads of said opening and an enlarged end adapted to engage an 50 ear lobe positioned in said U-shaped trough.

CARL SCHRAYSSHUEN.
